REBOUND PREVENTING TYPE BAR REST
FOR TYPEWRITING MACHINESHarold J. Kistner, Endicott, N. Y., assignor to
International Business Machines Corporation,
New York, N. Y., a corporation of New York

Application April 27, 1950, Serial No. 158,525

7 Claims. (Cl. 197—42)

1

This application relates to improvements in office machines, such as typewriters.

The broad object of the present invention is to provide a simple and effective means of preventing rebound of the type bars.

An object is to provide a means of preventing rebound which does not require any mechanical connections to type bars or the operating trains therefor.

An object is to provide means of preventing rebound which influences all of the type bars equally so as to simplify the problem of adjusting the type bars for even imprint.

An object is to provide a means of preventing rebound which contemplates the use of a magnet for restraining the type bar in its rest position.

An object is to provide a combined rebound preventing means and rebound cushion.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a section through the power operated type bar mechanism of an office machine.

Fig. 2 is a perspective showing a portion of the combined type bar cushion and rebound preventing means.

In the drawing there is disclosed a power operated type bar mechanism similar to the one disclosed in Patent No. 2,046,082 which discloses a well known machine for perforating accounting and statistical record cards and also typing on the top edge of such cards the interpretation of the perforations which may consist of either numbers or the letters of the alphabet. It will be understood, however, that the invention may be employed in other machines, such as conventional typewriters, since the means for preventing rebound is associated with the type bar mechanism and this mechanism, as disclosed in the above mentioned patent, is more or less conventional in general features of construction and similar to the type bar mechanisms of well known typewriters.

The type bars 10 are pivotally mounted on a fulcrum wire 11 in a curved segment 12, commonly known in the art as a wire segment because the pivot 11 is in fact a wire curved to conform to the shape of the segment 12. Only one type bar 10 is shown in Fig. 1, but it will be understood that, in accordance with usual practice, the segment 12 is curved so that the type bars

10 are mounted horizontally in a cylindrical array. Each type bar is slotted at 10a to receive a pin 13a carried by a sub-lever 13 pivoted on the fulcrum wire 14. This fulcrum wire is suitably supported by a cross frame member 15 supported by the side plates 16 forming part of the main framework of the machine. Cooperating with the shorter arm of the sub-lever 13 is an operating lever 15 carrying the pin 15a which cooperates with the edge of the short arm of lever 13. The lever 15 is pivoted on a fulcrum wire 17 suitably supported in the framework and, at its lower end, the lever 15 has pivoted thereto at 15b an operating hook 18. This hook has a lug 18a capable of engaging a continuously rotating power roller 19 which turns in a clockwise direction while the machine is in use.

The operating hooks 18 are controlled by the character keys 20 which are pivoted on the fulcrum wire 21 suitably supported in the framework. The keys 20 have downward extensions 20a each of which normally overlies a lug 18b on an associated operating hook 18 to prevent a tension spring 22 interposed between the lower end of the lever 15 and an extension of the hook 18 from rocking the hook 18 clockwise to engage the lug 18a with the power actuator 19. The extensions 20a are held in alignment with the lugs 18b by a comb 23 suitably mounted in the framework.

Also pivoted on the fulcrum wire 21, one for each key 20, are the non-repeat arms 20b each of which is connected to an associated extension 20a by a spring 24 and the arms 20b are slightly longer than the extensions 20a so that normally the lower end of each extension 20b is a little below and aligned with the top of the related lug 18b. The keys 20 are held up against a resilient stop 25 by the springs 26.

When any key 20 is depressed, the extensions 20a are rocked to the right, thereby tensioning the spring 24 since the arms 20b cannot follow the extensions 20a very far and thereby the spring 22 is permitted to rock the hook 18 clockwise to engage the lug 18a with the actuator 19. Thereupon said actuator draws the hook 18 to the left and rocks the lever 15 clockwise. Pin 15a, pressing down on the short arm of lever 13, rocks the latter counterclockwise and the pin 13a transmits this movement to the type bar 10 as a clockwise rotation to drive the type bar to the printing position. In the above patent, the type bar strikes the top edge of the card (not shown) through a suitable inking ribbon (not shown) but in a conventional typewriter the type bar will make its

impression against the usual cylindrical platen carrying a work sheet of some sort.

In most machines employing this type of type bar mechanism, the type bar returns with considerable velocity and tends to rebound from its initial position of rest and vibrate with a series of damped vibrations until the type bar finally comes to rest on the usual rest cushion. Ordinarily, some form of type bar rest and rebound cushion is provided which in the past has been designed to cushion the shock of return of the type bar and damp the vibration thereof as quickly as possible. However, such devices have not been wholly successful and in all machines having the disclosed type bar mechanism, the rebound of the type bars is a vexatious problem.

One of the difficulties arising from the rebound of the type bars is that it may be desired to use the same type bar a second time as in repeating characters and it sometimes happens that the power mechanism catches the type bar in part of an oscillation and starts to drive it to the printing position with the type bar already partly advanced to the printing position thereby causing the blow from a type bar which starts from an advanced position in such fashion to be different in strength from the blow starting from complete rest. Another difficulty is that a type bar may be in process of a rebound, particularly in the center of the type basket, while an adjacent one is in the initial stage of operation and the two sometimes collide and cause a jamming of the mechanism.

In order to avoid these difficulties, it is proposed to use a magnet which conveniently may take the form of a permanent magnet made from a very highly magnetic material such as now known under the name "Alnico V" which has the characteristics of very high magnetic strength with relatively small volume. In the drawings there is shown one illustrative form which such a magnet may take consisting of an arcuate channel shaped permanent magnet 27 which is disposed with its axis of cylindricity concentric with the axis of the cylindrical array of type bars on the type segment 12 and disposed so that the poles of the magnet influence the type bars in a zone approximately one-third of the distance from the end to which the type element is fixed to the pivot wire 11, the position of this zone not being critical. The sides 27a of the channel constitute the poles.

The type bars 10 are prevented from touching the poles 27a of the magnet 27 by means of a rebound cushion 28 which is secured to the magnet 27 by any suitable means, such as cement, and is located half way between the poles of the magnet throughout the length of the magnet 27 which confronts the type bars. The height in cross section, with reference to Fig. 1, of the cushion 28 is greater than the depth of the channel in the magnet 27 which forms the poles 27a of the magnet so that the type bars 10 normally are prevented from touching the poles. The cushion 28 may be made of any suitable resilient material such as rubber or plastic, which can withstand repeated blows, without materially losing its shape. Besides rubber there are a number of flexible plastics of which the well known Vinylite plastics are suitable.

The magnet 27 exerts a constant restraining force on the type bars 10 which, however, is insufficient to prevent the power mechanism, comprising the power actuator 19 and the operating hook 18, from actuating a type bar and the in-

fluence of the magnetic flux decreases very rapidly with the increase in the air gap between the type bars 10 and the poles 27a of the magnet 27 in accordance with well known principles of magnetic theory. Once the magnetic force is overcome in operating the type bar, the type bar will be propelled with increasing acceleration to the printing position. On the return stroke of the type bar, as soon as the type bar comes within the magnetic field of the magnet 27, the type bar is influenced by the magnet and the restoring force of the type bar due to the effect of the various springs and the inertia of the type bar itself is augmented by the magnetic field to restore the type bar against cushion 28 with a snap and the relatively great strength of the magnet in this position, once the power driving force is removed, is sufficient to prevent the type bar from vibrating more than very slightly on the cushion 28.

It will be understood that while it is most convenient to use a permanent magnet to prevent rebound, it is contemplated that electromagnets might be used, if desired.

The cushion 28 serves several purposes. One purpose is to produce a small gap between the poles of the magnet 27 and the type bars 10 so that it does not take an excessive amount of additional force to start the type bar away from the rest position, one that would be required if the magnet 27 were not present. On the return stroke of the type bar, the cushion 28 yields and allows the type bar to approach the poles of the magnet 27 more closely than in the rest position which, of course, greatly increases the effect of the magnetic field on the type bar with the result that, when the cushion 28 recovers from the shock of the blow, the type bar will be merely pushed back to its rest position relatively more slowly without any appreciable amount of vibrations and without passing materially beyond its rest position. Within the space of the gap between the poles of the magnet 27 and the type bars 10 enforced by the cushion 28, the poles of the magnet have considerably greater strength than at a relatively short distance from the poles with the result that the damping effect on the type bars is quite considerable, yet each type bar is permitted to restore to a position where the power required to separate it from the magnet is not so great as to require a considerable increase in the power exerted by the power mechanism to propel the type bar to the printing position.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a typewriting machine having a cylindrical array of type bars pivoted at their ends for a swinging movement inwardly from a rest position toward the axis of cylindricity to a printing position, rebound preventing means comprising a channel shaped permanent magnet disposed with its axis of cylindricity parallel with the axis of cylindricity of the type bars intermediate the ends of the latter and normal-

ly holding said type bars in their rest position. 2. In a typewriting machine having a printing member and means to move said member from a rest position to a printing position, the combination of a magnet for yieldingly holding the printing member in its rest position, said magnet being weak enough to permit the moving means to dislodge said printing member from rest position, and non-magnetic means to space said member from said magnet in the rest position of said member and operative to cushion its restoring movement from printing position by introducing an air gap between said magnet and said printing member which air gap is reduced when the printing member strikes said spacing means at the end of said restoring movement.

3. The invention set forth in claim 2 in which the spacing means comprises a resilient rebound cushion yielding in the direction of restoring movement of said member to permit the latter to move closer to said magnet to momentarily increase the effect of the magnet on said member.

4. The invention set forth in claim 2 in which the magnet comprises a bi-polar magnet of the horse-shoe type of which said member acts as an armature and the spacing means comprises a resilient rebound cushion located between the poles of the magnet.

5. The invention set forth in claim 1 provided with means normally to prevent the type bars from contacting the magnet when in their rest position and constructed to permit limited movement of the type bars from the rest position toward the poles of the magnet to cushion rebound and enable the magnet to momentarily act with greater force on said type bars.

6. In a typewriting machine, a printing member, means to propel the printing member from

5 a rest position to printing position, a magnet for holding the printing member in its rest position and operative to prevent rebound when the printing member is restored from the printing position, and yielding means to cushion rebound from the rest position located so that the rebound absorbing part of the stroke of the printing member is in a direction to temporarily increase the influence of the magnet, said yielding means forcing the printing member back to rest position after the shock of rebound has been absorbed.

10 15 20 25 7. In a printing machine, a printing element movable from a rest position to a printing position and including a member having motion between two limits one of which corresponds to said rest position, means to move said member away from its rest position to effect a printing stroke of said element, magnetic rebound preventing means strongly influencing said member in its rest position to resist movement of said member at the beginning of its printing stroke to a high degree but rapidly losing its influence with a small initial movement of said member away from rest position, and a yielding rebound cushion for controlling the influence of the preventing means when said member is restored to rest position.
